UNITED STATES PATENT OFFICE.

BOUDEWIJN B. NEUTEBOOM AND CECIL HAMELIN TAYLOR, OF DETROIT, MICHIGAN.

EXPLOSION-ENGINE.

1,160,438.

Specification of Letters Patent. Patented Nov. 16, 1915.

Application filed May 24, 1913. Serial No. 769,658.

To all whom it may concern:

Be it known that we, BOUDEWIJN B. NEUTEBOOM, a subject of the Queen of the Netherlands, and CECIL HAMELIN TAYLOR, 5 a citizen of the United States, residing at Detroit, county of Wayne, State of Michigan, have invented certain new and useful Improvements in Explosion-Engines, and declare the following to be a full, clear, 10 and exact description of the same, such as will enable others skilled in the art to which it pertains to make and use the same, reference being had to the accompanying drawings, which form a part of this specification.

15 Our invention relates to explosion engines and an object of our improvements is to provide an improved construction in which the various passages may be properly formed in the casting and in which said 20 passages may be effectively cooled, cleaned and inspected. We secure this object in the device illustrated in the accompanying drawings in which,

25 Figure 1, is a side elevation of an *en-bloc* casting of a four-cylinder engine, the cover plate being removed. Fig. 2, is an elevation of said cover plate separate from the casting. Fig. 3, is a section on the line C—C Figs. 1 and 2. Fig. 4, is a section 30 on the line D—D Figs. 1 and 2. Fig. 5, is a plan view, the head of the cylinder being removed and the plate shown secured in place at the side of the cylinder casting. Fig. 6, is an elevation showing the inside 35 of the cover plate. Fig. 7, is a section on the line G—G Figs. 1, 2 and 5.

a *a* is the part of the casting including the cylinders.

b indicates the removable cover plate.

40 The casting *a* is provided with a water jacket opening at the side near the top and into the casting and through the water jacket extend the intake passages *d d* and exhaust passages *e e e e*. These passages 45 extend to the various valves *j* and *k* and are surrounded by the water space *g*, *g* also opening at the side of the casting toward the top thereof.

50 *e* is a portion of an intake manifold formed in the casting *a*.

The water space *g*, the portion of the manifold *c* and the openings from the passages *e e e e* are surrounded by walls which are faced off at their outer edges.

55 The cover plate *b* is provided with an exhaust manifold *f* extending longitudinally

thereof along its upper portion and is provided with the complementary portion *c²* of the intake manifold and also with openings *i i i i* corresponding to and adapted to register with, the openings *e e e e* and opening into the exhaust manifold *f*. The cover plate *b* is cored out for a water space and is provided with openings *m m* communicating with said water space and with the water space *g* in the casting *a* when the cover plate is in place.

n n n are bolt holes in the casting *a* and *o o o* are corresponding holes in the cover plate *b*. The cover plate is placed against the sides of the cylinder *a*, the faced-off surfaces shown in Fig. 6 fitting against the faced-off surfaces above described upon the casting *a*, a proper joint is formed between the casting *a* and the cover plate *b*, and the cover plate is held in place by bolts passing into the apertures *m o*.

g² is the opening in which the cooling water passes into the water space of the cover *b* and thence through holes *m m* in the water space *g* of the casting *a*.

j, j, j, j are exhaust valves. *k k k k* are intake valves, these valves are in line with each other and their stems in one plane parallel to the plane of the axis of the cylinders in the casting *a*.

By this arrangement we secure a casting in which the various passages are formed with the water space surrounding them and the casting can be readily observed as to 90 the perfection of the walls of these passages, the intake passages may be completely clean including the intake manifold, and the parts may be readily assembled and the various cores easily and properly supported. 95

What we claim is:

1. A cylinder casting having an intake manifold, said casting consisting of two parts, the dividing plane between said parts passing longitudinally through said manifold so as to cut a main passage of said manifold longitudinally dividing it into two parts that are accessible for cleaning the interior walls when the parts are parted. 100

2. A cylinder casting having a water space, 105 an intake manifold and gas passages, said casting consisting of two parts, the dividing plane between said two parts passing longitudinally through said intake manifold and cutting said passages and space.

3. A cylinder casting having a water space, an intake manifold and gas passages,

said casting consisting of two parts, the dividing plane between said two parts passing longitudinally through said intake manifold and cutting said passages and space, said passages being surrounded by said water space so that the interior of their walls shall be accessible for cleaning when the parts are separated.

4. A cylinder casting consisting in part of 10 a removable plate, said casting having an intake manifold, an exhaust manifold, and water space so that the interior of their walls shall be accessible for cleaning when the parts are separated, a part of the intake 15 manifold being in said removable plate, valve passages and the complementary part of the intake manifold in the other of said parts, said plate being adapted to be secured to the other of said parts so as to complete 20 said intake manifold and secure a connection between the water spaces in the two parts, and a communication between the exhaust manifold and the exhaust passages of the other of said parts.
5. A cylinder casting consisting in part 25 of a removable plate, said casting having an intake manifold, an exhaust manifold and water space, a part of the intake manifold being in said removable plate, valve 30 passages and the complementary part of the intake manifold in the other of said parts,

said plate being adapted to be secured to the other of said parts so as to complete said intake manifold and secure a connection between the water spaces and the two parts, 35 and a communication between the exhaust manifold and the exhaust passages of the other of said parts, walls of said passages and manifolds being in said water space.

6. A casting embodying a plurality of 40 cylinders provided with gas passages and water space, said casting consisting of two parts divisible in a plane parallel to a plane through the axes of the several cylinders and cutting said passages and water space. 45

7. The combination with a plurality of cylinders, a plurality of valves therefor having their stems in one plane, passages leading to and from the ports of said valves, said cylinders being divided in a plane substantially parallel to the plane through the valve stems of said valves, said plane cutting said passages and adjacent water space so as to render the walls of the passage 50 accessible for cleaning. 55

In testimony whereof, we sign this specification in the presence of two witnesses.

BOUDEWIJN B. NEUTEBOOM.
CECIL HAMELIN TAYLOR.
